UNITED STATES PATENT OFFICE

2,191,566

LATTICE

Hubert Hill and Dewey O. Furr, Shreveport, La.

Application December 27, 1938, Serial No. 247,882

1. Claim. (Cl. 189—82)

The present invention relates to new and useful improvements in lattices for different purposes and has for its primary object to provide, in a manner as hereafter set forth, a device of this character embodying a novel construction, combination and arrangement of parts through the medium of which said device may be conveniently adjusted longitudinally to meet various conditions.

10 Other objects of the invention are to provide an extensible lattice of the character described which will be comparatively simple in construction, strong, durable, ornamental and attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an extensible lattice constructed in accordance with the present invention, showing the device in use.

Figure 2 is a view in vertical section, taken substantially on the line 2—2 of Fig. 1.

Figure 3 is a view in horizontal section through the device, the end portions thereof being broken away.

Figure 4 is an enlarged view in elevation of a corner portion of one of the frames and the adjacent parts.

Figure 5 is an enlarged elevational view of the lower inner corner portion of the slidable frame and the adjacent parts.

Figure 6 is a plan view of one of the guides.

Referring now to the drawings in detail, it will be seen that the embodiment of the invention which has been illustrated comprises a pair of substantially rectangular frames 1 and 2 of suitable metal. The frames 1 and 2 are similar in construction and are of the cross sectional shape shown to advantage in Fig. 2 of the drawings, said frames including substantially C-shaped outer portions 3 having formed integrally therewith spaced, opposed inwardly extending flanges 4. Mounted in the frames 1 and 2 are foraminous metallic sheets 5. The foraminous sheets 5 may be of expanded metal.

The frames 1 and 2 are adjustably connected for movement toward or away from each other by a lazy tong 6 which is connected, at its ends, to said frames through the medium of clips 7. As illustrated to advantage in Fig. 4 of the draw-

ings, the uppermost clips 7 are permanently fixed on the portions 3 of the frames 1 and 2 by welding, as at 8. The lowermost clips 7 are slidable on the frames 1 and 2, as shown to advantage in Fig. 5 of the drawings.

Mounted on the top and bottom of the frame 1 and projecting horizontally therefrom above and below the lazy tong 6 is a pair of guides 9 in which the frame 2 is slidable. The guides 9 terminate in substantially C-shaped, right angularly extending end portions 10 and 11 which accommodate the frames 1 and 2, respectively. As also shown to advantage in Fig. 4 of the drawings, the end portions 10 of the guides 9 are fixed to the top and bottom of the frame 1 by welding, as at 12. The frame 2 is slidable in the other end portions 11 of the guides 9.

It will thus be seen that a lattice has been provided which may be expeditiously adjusted longitudinally to meet various conditions. In Fig. 1 of the drawings, the device is shown in use between a pair of piers 13. However, it will be understood that the device may be used for any other purposes for which it may be found adapted and desirable, such as in vents in concrete or masonry walls. The frame 2 is slidable longitudinally in the guides 9 toward or away from the frame 1, the lazy tong 6 permitting any desired adjustment to be readily made within the range of said lazy tong, of course.

It is believed that the many advantages of an adjustable lattice constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

A lattice comprising a pair of frames, foraminous elements mounted in said frames, a lazy tong assembly located between the two frames, a pair of clips pivotally connected to the assembly at one end thereof, a second pair of clips pivotally connected with the assembly at the other end thereof, the upper clip of each pair being fixedly connected to its respective frame, the lower clip of each pair being slidably connected to its respective frame, a pair of elongated bars, means for firmly connecting one end of one bar to the top of the first frame, means for firmly connecting one end of the other bar to the lower part of said first frame, the bar connected with the upper end of the first frame extending over the top

- of the lazytong assembly, a clip connected to the other end of said last-mentioned bar and slidably engaging the top of the second frame, the bar which is connected with the under part of the
5 first frame extending under the lazytong assembly and having a clip fastened to its other end which slidably engages the under part of the

second frame, the clip-carrying ends of the bars being located adjacent the inner end of the second frame when the lazytong assembly is expanded.
